Patented Apr. 9, 1957

180,012

SALAD BOWL OR SIMILAR ARTICLE

Paul W. Buechler, Royal Oak, Mich.

Application December 21, 1953, Serial No. 28,159

Term of patent 14 years

(Cl. D44—15)

Figure 1 is a top plan view of a salad bowl or similar article showing my new design;

I claim:

The ornamental design for a salad bowl or similar article, as shown.
